THE BEARDSLEY & PIPER COMPANY, OF CHICAGO, ILLINOIS, A CORPORATION OF
ILLINOIS.

MOLDING MACHINE.

Application filed February 13, 1928. Serial No. 88,014.

The invention relates to molding machines of that type in which wads of sand are projected at high speed into flasks and which are provided with a projector-head which is movable horizontally to fill all portions of the flask or form all portions of the mold. One object of the invention is to provide improved raising and lowering mechanism for adjusting the projector-head into different positions and according to the height of the flasks into which the wads of sand are discharged.

Other objects of the invention will appear from the description.

The invention consists in the several novel features hereinafter set forth and more particularly defined by claims at the conclusion hereof.

In the drawings: Fig. 1 is a side elevation of a machine embodying the invention. Fig. 2 is a longitudinal section, parts being shown in elevation. Fig. 3 is a section taken on line 3—3 of Fig. 1. Fig. 4 is a section taken on line 4—4 of Fig. 2. Fig. 5 is a section on line 5—5 of Fig. 2. Fig. 6 is a section on line 6—6 of Fig. 5. Fig. 7 is a detail of the switch for controlling the motor which operates the jib raising and lowering mechanism.

The invention is exemplified in a machine of the general type exhibited in Patent No. 1,309,833 granted to us July 15, 1919, in which a projector-head is mounted on the free end of a horizontally swinging arm which is pivoted to the distal end of a jib to permit the projector-head to be moved horizontally to any desired point within a described range to project wads of sand into all portions of subjacent flasks. In the exemplification illustrated, the projector-head A comprises a casing a and a rotor a' provided with a projector blade a'' which coacts with the casing to shear wads of sand from a stream fed into the casing by a belt b' . The details of this projector-head may be in accordance with the construction set forth in an application filed by us Feb. 28, 1924, Serial No. 695,705. The shaft a^4 of the rotor extends longitudinally through the arm B, which is tubular for that purpose, to an electric motor D, the casing of which is fixed to the inner end of the arm B. This motor, be-

sides driving the projector-blade, drives the feed-belt b' through suitable gearing, as more fully exemplified in our Patent No. 1,408,493 dated May 7, 1922. A hopper b^2 is suitably supported from arm B to direct sand onto the belt b' . Said arm is pivoted to the outer end of jib C by a stud b^3 fixed to said arm and held in anti-friction bearings in a bracket c fixed to the outer end of the jib, to permit the arm to swing horizontally.

The jib C comprises an outer tubular member c' , and an inner member c^2 . The entire jib is adapted to swing horizontally, and the inner member c^2 is adapted to swing vertically to raise or lower the projector-head and its arm B, without interfering with the horizontal movement of the jointed structure, consisting of the jib and arm, and without varying the angle of delivery of the sand by the projector. The inner end of the jib-member c^2 is provided with a fork c^3 which is pivoted by the horizontal pin c^4 to a socket c^5 , which is mounted for horizontal rotation on a bracket or column c^6 which may be of any suitable construction. Anti-friction bearings c^7 are interposed between socket c^5 and the supporting column c^6 to render the jib freely movable in a horizontal plane. The outer end of jib member c^2 is pivoted, as at c^8 , to a bracket c^9 which is provided with a socket to receive, and is fixedly secured to, the tube forming the jib-member c' . The pivotal connection between member c^2 and the horizontally rotatable socket c^5 and the pivotal connection between the outer end of member c^2 and the inner end of member c' are adapted to permit member c^2 to be swung vertically to raise and lower the member c' and the projector-carrying arm which is pivoted to said member for horizontal rotation. To permit the projector-carrying arm B and the parts carried thereby to be bodily raised and lowered without varying their position relatively to the horizontal plane, a connection is provided between bracket c^9 and the horizontally rotatable socket c^5 . This connection consists of a pair of rods 20 and 21, which form, in effect, with the jib-member c^2 , a parallel linkage for supporting the jib-member c' and maintaining it in its horizontal

position. The inner ends of rods 20 and 21 extend through holes in the outer ends of a horizontal cross-shaft 23 which is pivotally mounted in the socket c^4 . The outer ends of rods 20 and 21 extend through holes in the ends of a horizontal cross-shaft 25 which is pivotally secured in and extends through the upper portion of bracket c^9 . Nuts 20 a are threaded to the ends of rods 20, 21 to space shafts 23, 25 apart to correspond with the distance between pivots c^4 , c^8 . When the jib-member c^2 is raised or lowered to correspondingly effect the horizontal plane of movement of the projector-head, rods 20, 21 will permit this adjustment and maintain the horizontally of the projector-carrying arm B, so that the angle at which the sand is delivered by the projector will not be varied, while the projector remains free to be shifted horizontally to fill all portions of the flasks.

Power-operated mechanism is provided for swinging the jib-member c^2 vertically to raise and lower the projector and sand-feeding mechanism. An electric motor 30 is fixedly mounted on member c^2 and coupled to directly drive a shaft 31 which is journaled in and extends into a gear-housing 32 which is integrally formed with the member c^2 . Housing 32 is provided with a removable side-head 32 a to provide access to the gearing in the housing and with removable end-heads 32 b . A worm 33, fixed to shaft 31, meshes with a worm-gear 34 which is fixed to a cross-shaft 35 which is journaled in the lower portion of the housing 32. A winding drum 36 is fixedly secured to one projecting end of shaft 35, and a winding drum 37 is fixedly secured to the opposite projecting end. A cable 38 has its ends coiled around and secured to the drums respectively, and comprises a vertically extending loop 39 above the drums, which passes over a pair of sheaves 40 and 41 which are rotatably mounted on arms 42 respectively, which are integral with, and project outwardly and upwardly from, the socket c^5 . Drums 36 and 37 have their peripheries grooved to guide the windings of the cable 38 and are of differential size, so that when they are both conjointly rotated in one direction, as the result of the rotation of shaft 35, one drum will pay out or take up the cable faster or slower than the other takes it up or pays it out, thus resulting in the shortening and lengthening of the loop 39 and correspondingly raising and lowering the jib-member c^2 which is suspended by the cable. The ends of the cable are reversely wound on the drums, so that, as one drum pays out the cable, the other drum will take it up at a differential rate of speed as aforesaid. Motor 30 is of the reversible type.

To insure the stopping of the motor when the jib-member c^2 has reached either of its extreme positions, provision is made for automatically opening the switch which controls the operation of motor 30. This switch is mounted in a box 45 a , and comprises an arm 45 fixed to a shaft 45 c (Fig. 7) and provided with a contact 45 a which is adapted to engage stationary contacts 45 b , 45 c . These contacts are connected, as well understood in the art, to control the motor and its direction of operation. Contact 45 is adapted to be swung into engagement with either of said contacts 45 b and 45 c , and when it is between them, the motor circuit will be interrupted. A handle 46 is fixed to the outer end of shaft 45 c , so that arm 45 may be swung into position to close the circuit, either through contact 45 c or contact 45 b , according to the direction in which the motor is to travel to shift the jib. A perforated stud 47 is connected to an arm on the handle 46 and a rod 48 extends loosely through said stud. Said rod has one of its ends pivoted to a lug 49 which is fixed to the fork c^3 which forms a part of the jib-member c^2 , so that the rod will swing with said fork. Adjustable abutments 50 and 51, such as nuts, are screw-threaded to a rod 48 and are adapted to engage the stud 47 to open the switch when jib-member c^2 reaches its extreme raised or lowered position respectively. By shifting the handle 46 in one direction, the arm 45 will close the switch to cause the motor to be operated in one direction until the handle is manually shifted to open the circuit or until it is automatically shifted by one of said abutments. By shifting the handle 46 in the opposite direction, a circuit for reversely operating the motor will be closed until the handle is manually shifted to open the switch or the other abutment engages the stud 47 to automatically open the switch.

An endless belt 60, carried by pulleys 61 and 62, feeds sand from a hopper 63 into the chute b^2 which is carried by and movable with the projector-supporting arm B which also supports the feed-belt b . Pulley 61 is driven by a suitable gearing and a motor contained in a housing 64 which is fixedly secured to the top of, and rotates with, the socket c^5 , as well as with the jib. The shaft 65 for idler pulley 62 is carried by a pair of members 66 which have their inner ends pivoted to swing around the shaft of pulley 61. Each member 66 comprises a pipe or tube 67 and a bearing 68 for one end of shaft 65 having a screw 69 extending into one of the tubes and adapted to be adjusted by a nut 70 to adjust the shaft 65 inwardly or outwardly to keep the endless belt 60 taut. Arms 71 are fixedly and adjustably secured by screws 72 in the bracket c^9 , and these arms support the outer ends of the belt supporting members 66. A deflector 73 is supported by arms 71, to direct sand from belt 60 into chute 62. Arms 71 are raised and lowered vertically in a rectilinear path with the jib-member c^2 , and correspondingly raise

and lower the outer end of the feed-belt 60 with the vertical adjustment of the projector and the sand-feeding belt b' .

In operation, the sand will be continuously fed in regulated quantities from the hopper 63 to belt 60 which will discharge it into chute b^2 and onto belt b' which will feed the sand into the projector. The latter is movable horizontally around the pivotal connection 10 between the arm and the jib and also around the axis about which the jib swings, so that the head may be easily moved to project wads of sand into all portions of a subjacent flask. When it is desired to raise or lower 15 the projector head, the jib member c^2 will be swung vertically until the projector is positioned in the desired elevation. To effect this raising and lowering, the operator will close the switch 45 to close the circuit through the 20 motor 30 which is of the reversible type, so that it may be operated in either direction. When operated in one direction, it will, through a reducing gearing 33, 34 drive the shaft 35, on which both of the drums 36 and 25 37 are fixed. By reason of the differences of the diameters of the drums, the larger drum will wind up the cable 38 faster than it is paid out by the drum 36, thus shortening the loop 39 and causing the jib-member c^2 to 30 swing upwardly from its pivot c^4 . This vertical swinging will raise the pivot c^8 between the members c' and c^2 of the jib and the rods 20 will swing in parallelism with the member c^2 to maintain the horizontality of the member c' , so that the projector-supporting arm 35 B will remain horizontal and the angle of delivery of the sand by the projector will not be changed. The jib-operating mechanism, consisting of the drums and cable, are of such 40 character that they will support the jib in any position without additional locking means. When the switch 45 is shifted to operate the motor 30 in reverse direction, the loop 39 of the cable will be lengthened and the jib-member c^2 will swing downwardly and lower 45 the projector and its supporting arm without changing their position with respect to the horizontal plane. In raising and lowering the member c^2 , the supports 66 for the upper 50 sand conveyor belt 60 will swing about the shaft of pulley 61, so that the outer end of the belt will be raised and lowered correspondingly to the chute b^2 which is carried by the supporting arm B. The nuts 70 rest on the 55 arms 71, so the members 66 will rise and fall with jib-member c' . In event the operator should fail to open the switch 45 before the jib-member c^2 reaches its upper or lower limit of movement, the abutment nuts 50, 51 will 60 engage stud 47 and shift the switch lever 46 to open the switch.

The invention exemplifies a molding machine of the sand projector type in which the projector is movable horizontally over

flasks, and in which provision is made for 65 raising and lowering the projector by means of a vertically swinging jib-member; also, a structure of this character in which said member is power-operated and in which the lifting connection is self-locking. The invention 70 also exemplifies an automatic switch cut-off for the jib-operating motor, so that it will stop when said member reaches either of its extreme positions.

The invention is not to be understood as 75 restricted to the details set forth, since these may be modified within the scope of the appended claims, without departing from the spirit and scope of the invention.

Having thus described the invention, what 80 we claim as new and desire to secure by Letters Patent, is:

1. In a molding machine, the combination of a projector, means for supporting the projector comprising a member pivoted to swing 85 vertically to raise and lower the projector mechanism mounted on the supporting means for driving the projector and means for vertically swinging said member.

2. In a molding machine, the combination 90 of a horizontally movable projector, means for supporting the projector comprising a member pivoted to swing vertically to raise and lower the projector mechanism mounted 95 on the supporting means for driving the projector, and means for vertically swinging said member.

3. In a molding machine, the combination of a horizontally movable projector, a motor for driving the projector movable therewith, 100 means for supporting the projector comprising a member pivoted to swing vertically to raise and lower the projector, and means for swinging said member.

4. In a molding machine, the combination 105 of a projector, means for supporting the projector comprising a horizontally rotatable member pivoted to swing vertically to raise and lower the projector, and mechanism for raising and lowering said member.

5. In a molding machine, the combination 110 of a projector, means for supporting the projector comprising a horizontally rotatable member pivoted to swing vertically to raise and lower the projector, mechanism mounted 115 on the supporting means for driving the projector, and mechanism for raising and lowering said member rotatable horizontally therewith.

6. In a molding machine, the combination 120 of a projector, means for supporting the projector comprising a structure pivoted to swing vertically to raise and lower the projector, mechanism mounted on the supporting means for driving the projector, and means for vertically swinging the structure, said structure comprising a pair of parallel swinging members to cause the projector to 125

move rectilinearly during the swinging movement of the structure.

7. In a molding machine, the combination of a projector, means for supporting the projector comprising a structure pivoted to swing vertically to raise and lower the projector, mechanism mounted on the supporting means, for driving the projector, a horizontally movable projector carrying arm pivoted to one end of the structure, and means for vertically swinging the structure, said structure comprising a pair of parallel swinging members to cause the projector and said arm to move rectilinearly during the swinging movement of the structure.

8. In a molding machine, the combination of a projector, means for supporting the projector comprising a horizontally rotatable structure pivoted to swing vertically to raise and lower the projector, mechanism mounted on the supporting means for driving the projector and means for vertically swinging the structure, said structure comprising a pair of parallel swinging members to cause the projector to move rectilinearly during the swinging movement of the structure.

9. In a molding machine, the combination of a projector, means for supporting the projector comprising a horizontally rotatable structure pivoted to swing vertically to raise and lower the projector, mechanism mounted on the supporting means for driving the projector, and a horizontally movable projector carrying-arm pivoted to one end of the structure, and means for vertically swinging the structure, said structure comprising a pair of parallel swinging members to cause the projector and said arm to move rectilinearly during the swinging movement of the structure.

10. In a molding machine, the combination of a projector, means for supporting the projector comprising a horizontally rotatable member pivoted to swing vertically to raise and lower the projector, mechanism mounted on the supporting means for driving the projector, mechanism for raising and lowering said member, and means for feeding sand to the projector in all of its positions.

11. In a molding machine, the combination of a projector, driving mechanism for the projector including a motor movable with the projector, means for supporting the projector and the driving mechanism comprising a horizontally rotatable member pivoted to swing vertically to raise and lower the projector, and mechanism for raising and lowering said member.

12. In a molding machine, the combination of a projector, means for supporting the projector comprising a member pivoted to swing vertically to raise and lower the projector, means for vertically swinging said member, mechanism for driving the projector mount-

ed on and movable with said member, and means for feeding sand to the projector comprising a conveyor pivoted to swing vertically with said member.

13. In a molding machine, the combination of a projector, means for supporting the projector comprising a horizontally rotatable member pivoted to swing vertically to raise and lower the projector, mechanism for driving the projector, mounted on and movable horizontally and vertically with said member, means for vertically swinging said member, and means for feeding sand to the projector comprising a conveyor pivoted to swing vertically and rotate horizontally with said member.

14. In a molding machine, the combination of a projector, driving mechanism comprising a motor movable with the projector, means for supporting the projector comprising a horizontally rotatable member pivoted to swing vertically to raise and lower the projector with its driving mechanism, means for vertically swinging said member, and means for feeding sand to the projector in all of its positions comprising a conveyor pivoted to swing vertically and horizontally with said member.

15. In a molding machine, the combination of a projector, means for supporting the projector comprising a horizontally swinging arm and a jib pivoted to swing vertically to raise and lower the arm, mechanism for driving the projector mounted on and movable with the jib, and means for raising and lowering the jib, the arm being pivoted to the jib.

16. In a molding machine, the combination of a projector, means for supporting the projector comprising a horizontally swinging arm, and a jib pivoted to swing vertically to raise and lower the arm and pivoted to swing horizontally, mechanism for driving the projector mounted on and movable with the jib, and means for raising and lowering the jib, the arm being pivoted to the jib.

17. In a molding machine, the combination of a projector, means for supporting the projector comprising a horizontally swinging arm and a jib pivoted to swing vertically to raise and lower the arm and pivoted to swing horizontally, the arm being pivoted to the jib, mechanism for driving the projector mounted on and movable with the jib, means for raising and lowering the jib, and means for feeding sand to the projector comprising elements movable with the arm and the jib respectively.

18. In a molding machine, the combination of a projector, means for supporting the projector comprising a horizontally swinging arm and a jib pivoted to swing vertically to raise and lower the arm, mechanism for driving the projector mounted on and movable with the jib, means for raising and lowering

the jib, the arm being pivoted to the jib, and a motor connected to drive the projector mounted on and movable with said arm.

19. In a molding machine, the combination 5 of a projector, means for supporting the projector comprising a horizontally swinging arm and a jib pivoted to swing vertically to raise and lower the arm and pivoted to swing horizontally, the arm being pivoted to the jib, 10 mechanism for driving the projector mounted on and movable with the jib, means for raising and lowering the jib, a motor for driving said projector mounted on and movable with said arm, and means for feeding sand to 15 the projector comprising elements movable with the arm and the jib respectively.

20. In a molding machine, the combination 20 of a projector, means for supporting the projector comprising a member pivoted to swing vertically to raise and lower the projector, mechanism for driving the projector mounted on and movable with said member, means for raising and lowering said member, and means for causing the projector to move 25 bodily and vertically during the vertical swinging movements of the jib.

21. In a molding machine, the combination 30 of a projector, driving means for the projector comprising a motor movable with the projector, means for supporting the projector and its driving mechanism comprising a member pivoted to swing vertically to raise and lower the projector and pivoted to swing horizontally, means for swinging the member 35 vertically, and means for causing the projector to move bodily and vertically during the vertical swinging movements of the jib.

22. In a molding machine, the combination 40 of a sand projector, means for supporting the projector comprising a member pivoted to swing vertically, driving mechanism for the projector mounted on the supporting means and movable with the projector, and mechanism for swinging the member to raise and 45 lower the projector comprising a plurality of differential drums and a cable operated thereby.

23. In a molding machine, the combination 50 of a projector, means for supporting the projector comprising a member pivoted to swing vertically, driving mechanism for the projector mounted on the supporting means and movable with the projector, and mechanism for swinging the member to raise and lower 55 the projector comprising a plurality of differential drums, and a cable operated thereby, a horizontally rotatable bracket to which the member is pivoted, and means on the bracket over which the cable is looped.

24. In a molding machine, the combination 60 of a projector, means for supporting the projector comprising a member pivoted to swing vertically, driving mechanism for the projector mounted on the supporting means and

movable with the projector, and mechanism 65 for swinging the member to raise and lower the projector comprising a motor, a plurality of differential drums and a cable operated thereby, said motor and drums being mounted on said member.

25. In a molding machine, the combination 70 of a projector, means for supporting the projector comprising a horizontally rotatable bracket, a member pivoted to said bracket to swing vertically, mechanism for swinging 75 the member to raise and lower the projector comprising a plurality of differential drums, a cable operated thereby, a motor, reducing gearing for driving the drums mounted on and vertically movable with said members, 80 and means on the bracket over which the cable is looped.

26. In a molding machine, the combination 85 of a projector, means for supporting the projector comprising a horizontally rotatable jib composed of a member pivoted to swing vertically and a member pivoted to the outer end of the jib to swing horizontally, driving mechanism for the projector mounted on and movable with the jib, means for raising and lowering the vertically swinging member, and means operative to retain the other member in a horizontal position during said vertical movement.

27. In a molding machine, the combination 90 of a projector, means for supporting the projector comprising a horizontally rotatable jib composed of a member pivoted to swing vertically and a member pivoted to the outer end of the jib to swing horizontally, driving mechanism for the projector mounted on and movable with the jib, means for raising and lowering the vertically swinging member, means for causing the other member to move 100 bodily during said vertical movement, and an arm pivoted on the bodily movable member to swing horizontally, the projector being mounted on the outer end of said arm.

28. In a molding machine, the combination 105 of a projector, means for supporting the projector comprising a horizontally rotatable jib composed of a member pivoted to swing vertically and a member pivoted to the outer end of the jib to swing horizontally, driving mechanism for the projector mounted on and movable with the jib, means for raising and lowering the vertically swinging member, means for causing the other member to move bodily during said vertical movement, an 110 arm pivoted on the bodily movable member to swing horizontally, the projector being mounted on the outer end of said arm, and driving mechanism for the projector mounted on and movable with said arm.

29. In a molding machine, the combination 115 of a projector, means for supporting the projector comprising a horizontally rotatable jib pivoted to swing vertically to raise and lower

the projector, a motor for vertically shifting the jib, a switch for controlling the motor, and means for automatically opening the switch when the jib reaches a predetermined position.

30. In a molding machine, the combination of a projector, means for supporting the projector comprising a horizontally rotatable jib pivoted to swing vertically to raise and lower the projector, a motor for vertically shifting

the jib, a switch for controlling the motor, and means for automatically opening the switch to stop the motor when the jib reaches either end of a predetermined range of movement. ¹⁵

Signed at Chicago, Illinois, this 2nd day of February, 1926.
